PULL BOX REMOTE CONTROL

Daniel Mapes, Upper Montclair, N. J., assignor to
 Walter Kidde & Company, Inc., New York,
 N. Y., a corporation of New York

Application April 1, 1931, Serial No. 526,973

3 Claims. (Cl. 177—372)

The present invention relates to controlling mechanisms for systems which are normally inoperative but adapted to be operated upon a predetermined actuation of a controlling mechanism and embodies, more specifically, an improved form of pull box remote control which is adapted to actuate systems of the above character, its construction being such as to facilitate, materially, the actuating operation thereof without danger to the operator by reason of the possible presence of the exposed edges of shattered glass.

The control boxes now available are generally of a type wherein a plate of glass or other fracturable material encloses the manually actuating controlling element of the pull box. Operation of these existing devices requires the shattering of the glass and then the act of reaching into the box and grasping the manual actuating device. This latter act is frequently dangerous by reason of the fact that particles of shattered glass are present in the box and frequently expose dangerous cutting edges. Furthermore, the existing mechanisms are loosely assembled and frequently rattle due to vibration of the box.

To overcome the disadvantages noted above, the present invention has been designed and an object thereof is the provision of a pull box remote control of improved form, the elements of which are simple in construction, assembly, operation and maintenance.

A further object of the invention is to provide a control device of the above character, wherein a fracturable plate is employed to retain the manually actuated element normally, the elements of the box being so constructed as to prevent rattling thereof due to vibrations which may be impressed thereon.

A further object of the invention is to provide, in a box of the above character, a manually actuated controlling element which is normally enclosed by a fracturable plate but which automatically presents itself for actuation in an exposed and readily accessible position outside of the control box when the plate is fractured.

Further objects, not specifically enumerated above, will be apparent as the invention is described in greater detail in connection with the accompanying drawing, wherein:

Figure 1 is a view in front elevation showing a pull box remote control mechanism embodying the present invention.

Figure 2 is a view in side elevation, showing the box of Figure 1.

Figure 3 is a view in section, taken on line 3—3

of Figure 1, and looking in the direction of the arrows.

Referring to the above drawing, a sheet metal wall box 10 is formed preferably by stamping and is provided with three abutments 11 which are adapted to receive and position a fracturable plate as described in detail hereinafter. The box is made of a convenient size and is formed with a cylindrical, internally threaded projection 12 which is adapted to be connected to any suitable conduit. The neck of the pull box which forms the entrance to the extension 12 is preferably rounded, as at 13, to form a seat for a knob 14. This knob is formed with a cooperating rounded seat portion 15 which is adapted to engage the seat 13 snugly.

The knob 14 is formed with an extension 16 which carries a pin or pins 17 extending in opposite directions transversely to the axis of the knob. Upon this pin, a handle 18 is journaled, springs 19 being anchored to the hinged extremities of the handle and to the pin or knob extension. The tendency of springs 19 is to urge the handle normally into a position such as shown by dot and dash lines in Figure 3, which position lies outside of the box 10.

Bosses 20 are formed on the handle 18 and are adapted to engage a glass or other fracturable plate 21 which is seated against the abutments 11 and secured in position by means of a cover plate 22. Plate 22 is secured to flanges 23, formed on the box 10, by means of screws 24 and may be provided with a hammer recess 25. Within the hammer recess a hammer 26 may be inserted, being removably secured in such position by means of a spring clip 27, as clearly shown in Figures 1, 3, and 4. The hammer is preferably secured to the cover plate 22 by means of a chain 28 which is secured to the rear side of the cover at 29 and extends through an aperture 30. Knob 40 14 is secured to an operating cable 31 to actuate any suitable mechanism in a manner which will be readily apparent. Upon fracturing the glass with the hammer 26 the handle 18 immediately springs into its projecting position, as shown in dot and dash lines in Figure 3. In this position, actuation of the mechanism is readily effected without danger of injury due to fragments of the shattered glass. Not only do the springs 19 urge the handle into its projecting position but these springs cause the bosses 20 to engage the plate 21 and urge the same against the cover plate 22, at the same time seating the knob 14 snugly against the seat 13. In this fashion, objectionable rattling is prevented.

- From the foregoing, it will be seen that the control mechanism may be utilized in any type of system, whether mechanical, pneumatic, electrical or other fluid type. Not only do the springs 5 19 cause the handle to be moved into its extended position, but they facilitate the fracturing of the plate 21. The springs furthermore close the outlet of the conduit pipe regardless of the tension on the cable 31.
- 10 It will be observed that the manner in which the fracturable plate is mounted facilitates the complete release of the shattered fragments of the glass or plate and permits them to fall freely therefrom. Instead of being clamped in the box 15 whereby the sides of the plate tend to remain in position, such fragments fall free of the box and thus prevent danger of injury due thereto. In combination with these spaced circumferential abutments for supporting the glass plate, the 20 handle is provided with abutments which engage the plate at points spaced from the circumference of the plate and apertures. This further facilitates the freeing of all fragments of glass from the housing.
- 25 The specific handle construction, as well as the construction of the associated elements may be varied as desired without departing from the scope of the invention as defined in the appended claims.
- 30 I claim as my invention:
1. In a box having a cover plate, means thereon mounting a fracturable disc, a recess formed in the cover plate, a spring clip in the recess, a hammer in the recess removably held by the 35 spring clip, said recess being of such size as to accommodate the hammer and having an aperture, and extensible means passing through the aperture and securing the hammer to the rear of the cover plate.

2. A box, actuating means movable with respect to the box, a seat on the box for the actuating means, a handle on the actuating means, fracturable closure means for the box normally maintaining the handle in a retracted position, means to maintain the actuating means seated and to move the handle with respect to the box and the actuating means when the said closure means is fractured, means to position said closure means on said box, means to secure said closure means against said last named means, and means on said handle bearing against the closure means whereby the fractured portions of the closure means tend to fall clear of the box upon fracture 15 of the closure means.
3. A break-glass box comprising a body portion, an actuating means movable with respect to the box, a cylindrical extension on the box and having a curved self-nesting seat for the actuating means, a handle on the actuating means, a fracturable plate forming a closure for the box and normally engaging the handle to maintain the same in a retracted position, a spring between the actuating means and the handle to urge the 20 handle against the plate and maintain the actuating means seated and to move the handle with respect to the box and actuating means when the plate is fractured, at least three spaced circumferential abutments on the body portion to 25 position the plate, an apertured cover carried by the body portion to secure the plate against the abutments, and means on the handle spaced from the circumference of the aperture and bearing on the plate, whereby the fractured portions 30 of the plate tend to fall clear of the aperture upon fracture of the plate.

DANIEL MAPES.
